PUMP AND STROKE ADJUSTING
MECHANISM

Harry J. Anderson and Milton V. Hartman, Chicago, Ill., assignors to Hills-McCanna Company, Chicago, Ill., a corporation of Illinois

Application February 5, 1945, Serial No. 576,180

18 Claims. (Cl. 103—38)

1

This invention relates to piston or displacement type pumps and to means for adjusting the stroke thereof.

An object of the invention is to provide a novel means for adjusting the stroke of piston or displacement type pumps.

Another object of the invention is to provide a piston or displacement type pump equipped with a hydraulic stroke adjustment means.

Still another object of the invention is to provide a novel pump capable of pumping two different liquids simultaneously in varying proportions.

Other objects of the invention will become apparent from the following description and drawings of which:

Figure 1 is a plan view with a fragment in cross-section of the novel stroke adjusting device and pump;

Figure 2 is a vertical cross-section of the novel stroke adjusting device and pump taken on the line 1—1 of Figure 1;

Figure 3 is an enlarged plan view with a fragment in cross-section of the driving mechanism for the stroke adjusting device and pump;

Figure 4 is an enlarged vertical cross-section taken on the line 4—4 of Figure 2, showing the details of the inlet and outlet valves of the stroke adjusting device; and

Figure 5 is an enlarged horizontal cross-section through the center of a clutch shown in Figure 1.

Figure 6 is an enlarged isometric view of a roller and guide blocks forming part of the device.

Referring to the drawings, the numeral 1 represents a casing in which all moving parts of the stroke adjusting device are enclosed with the exception of a portion of the crankshaft 3 which projects beyond the side of the casing in order that it may be connected to a suitable source of power capable of imparting thereto rotary motion at the desired speed. The casing is provided with flanges 5 extending horizontally from the bottom of the casing, provided with holes 7 so that the casing may be bolted firmly to a suitable foundation. The casing is also provided with a drain plug 8 at the bottom of the side wall.

The crankshaft is rotatably supported by roller bearings 9 (Fig. 1) held in place between two sets of inner bearing races 11 and outer bearing races 13. Inner cylindrical spacer 15 and outer cylindrical spacer 17 are provided between the two sets of inner and outer bearing races. The roller bearings and races are enclosed in a cylindrical housing 19 which is rigidly bolted to the side of the casing 1 by means of threaded bolts 21,

2

which pass through suitable holes 23 in the flange 25 of the housing 19 and screw into threaded recesses tapped in the side of the casing in alignment with the holes 23. An end plate 27 having a circular opening in the center thereof to accommodate the shaft 3 is bolted to the housing 19 by means of threaded bolts 29 passing through holes 31 in the plate and adapted to be screwed into threaded recesses tapped in the housing in alignment with the holes 31. A ring seal 33 adapted to fit in a recess in the end plate 27 provides a seal between the shaft 3 and the end plate to prevent leakage of oil.

The inner end of crankshaft 3 is rigidly fastened to crank 35. As is shown in Figures 1 and 3, a crankarm 37 is fastened to crank 35 eccentrically with respect to crankshaft 3. The crankshaft, crank and crankarm are preferably cast and/or machined as a single unit. The crankarm extends horizontally from the side of the crank opposite that to which the crankshaft is fastened. The crankarm 37 is adapted to rotate on roller bearings 39 held in place by inner bearing race 41 and outer bearing race 43. The races 41 and 43 are held in place between washers 45 by means of a snap ring 47 which fits in an annular groove on the free end of the crankarm 37.

The outer bearing race 43 is confined between two spaced vertical rectangular plates 49 and 51 having hardened, machined surfaces. Each plate is fastened to the inside of a split cross-head 53 comprising the two halves 55 and 57 bolted together by means of four bolts 59 threaded at their ends to receive nuts 61. Each plate 49 and 51 is fastened to its respective half of the cross-head by means of screws 63 and countersunk screws 64 adapted to pass through holes 65 in the plates 49 and 51 along the edges thereof and to screw into threaded recesses 67 tapped into each half of the cross-head. The plates 49 and 51 are drilled and the cross-head halves are tapped identically along both edges in order to permit them to be turned periodically and thereby equalize wear thereon. The crankarm 37 with the roller bearings 39 and bearing races 41 and 43 is adapted to reciprocate in a vertical direction between the plates 49 and 51.

Each half 55 and 57 of the cross-head 53 is formed integrally with a horizontally extending cylinder 69 adapted to reciprocate in a bearing 71 held tightly in place in bore 73 in the end of the casing 1. Passageways 75 are provided to permit breathing and ingress and egress of oil to and from the space 76.

The stroke adjusting device and pump may be formed with two identical counterparts, one on each side of the median line C—C for feeding a different liquid from each side. The unit shown in the drawings is designed for single feed and hence only the portion of the unit on the right side of the median line has been equipped with the necessary valves, plungers, adjusting mechanism, etc. It is to be understood, however, that where both ends of the unit are used to feed liquid the left half of the apparatus will be a mirror image of the right half.

Referring now particularly to Figures 2 and 4, the cylinder 69, adjacent the juncture with the right half 51 of the cross-head has two diametrically opposite threaded bores 75 and 77 tapped therethrough to accommodate inlet and outlet valves, indicated generally by the numerals 79 and 81, respectively. The inlet or suction valve comprises the seat 83 having a threaded stem 85 adapted to be screwed into the bore 75 and having an axial passageway 87; a body 89 adapted to be screwed onto the outer end of the seat 83 and locked in place by nut 90; and a steel ball 91. The steel ball is prevented from rising too high and closing off passageway 87 by means of the pin 92 extending across the passageway a short distance above the ball. The body 89 has an axial bore 93 terminating short of the outer end thereof and a threaded horizontal bore 95 from the outside to the bore 93. An oil filter 97 is adapted to be screwed into the bore 95. The ball 91 closes the passageway through the valve on the discharge-stroke of the pump.

The outlet or discharge valve 81 comprises the seat 99 having the threaded stem 101 adapted to be screwed into the bore 77 and having an axial passageway 103; a body 105 adapted to be screwed onto the outer end of the seat 99 and locked in place by nut 107; steel balls 109 and 111 separated by the helical spring 113; and a T-shaped passageway 115 in the body 105 for permitting escape of oil or other hydraulic fluid from the cylinder 69. As is shown on the drawing the helical spring 113 holds the balls 109 and 111 on their respective seats. The body 105 has a vertical axial bore 117 extending downwardly from the top thereof to a short distance below the cross-member of the T-shaped passageway 115 and of larger diameter than the stem portion of the T-shaped passageway 115. The bore 117 accommodates a plunger 119 having a smaller bottom portion 120 which engages the ball 111. A roller 121 is rotatably mounted in the plunger 119 adjacent the top thereof with the top of the roller extending beyond the top of the plunger.

The cylinder 69 is also provided, adjacent the juncture thereof with the right half 51 of the cross-head, with a relief valve 122, composed of a body 123 having a small T-shaped passageway 124; a larger axial bore 125 threaded at its outer end to receive adjustable screw plug 126 held in position by cotter pin 127; steel ball 128 and helical spring 129 adapted to hold the ball 128 on its seat.

A seal plug 130 having a recess to accommodate seal ring 131 fits snugly in the end of the cylinder 69 adjacent drive plate 51. The central thickened portion 132 of the plug 130 is press-fitted into the recess 133 in the drive plate 51.

Referring now to Figures 1 and 2, a bracket 134 is bolted by means of bolts 135 to the side of the casing opposite the side from which the crank-shaft 3 projects, at a point adjacent the top thereof and exactly along the median line C—C.

The bracket 134 is provided with two, vertically spaced horizontal bores 136 and 137 along lines directly above roller 121. A horizontal, cylindrical stem 138, having a portion thereof threaded as shown at 139 is rotatably supported at one end by the bore 136 in bracket 134 and passes through a bore in the end wall of the casing. The end of the stem 138 projecting outside the casing is provided with a handwheel 140. An elongated cam 141, threaded at one end to engage the threads 139 of the stem 138, is mounted on the stem and adapted to travel back and forth thereon upon turning the stem. A guide rod 142 is mounted directly above the threaded portion 139 of the stem. One end of the rod 142 is supported in the bore 137 in bracket 134 and held fast by set screw 143. The other end of the rod 142 rests in a slot 144 on the top side of the cam 141 and prevents the cam from rotating with the rotation of the stem.

The bottom, left end 145 of the cam 141 is bevelled to engage roller 121 and depress it.

A gear 147 is rigidly mounted on the stem 138 by means of set screw 149 against the inside wall of the casing. As is apparent from the drawing stem 138 cannot move in a horizontal direction.

As shown in Figures 1 and 5 a reversible electric motor 151 is fastened by means of screws 153 to the same side wall of the casing and at the same level as bracket 134. The motor 151 is adapted to drive a gear 155 through a clutch mechanism indicated generally by the numeral 157. The clutch comprises a plate 159 rigidly mounted on the motor shaft 161 by means of a set screw 163, a driven plate 165 formed with a stem 167 upon which gear 155 is rigidly mounted by means of set screw 169, a helical spring 171 mounted in a recess in stem 167, a steel ball 173, a spring retainer 175 between ball 173 and spring 171, and a drum 177 threaded to screw onto plate 159 and having a central bore to accommodate stem 167. The drum 177 is rigidly mounted on plate 159 by means of set screw 179. The spring 171 holds the adjacent faces of plate 165 and drum 177 in contact with each other. Gear 155 meshes with gear 147. The end of the stem 167 is supported in a recess in the end wall of the casing.

It will be understood that the motor and clutch may be omitted and the cam 141 adjusted by turning handwheel 140 instead of by operation of motor 151.

Still referring to Figures 1 and 2, the numeral 183 indicates a sump adapted to be filled with oil and having a drain plug 184 at the bottom thereof. The sump 183 is fastened to the end of case 1 by means of studs 185 and nuts 187. A ring seal 189 is provided between the casing and sump to prevent leakage. The wall 191 of the sump is provided with a horizontal bore co-axial with cylinder 69. A plunger 193 extends from cylinder 69 through the bore in wall 191 into sump 183. The plunger 193 is mounted to reciprocate in a bushing 195 rigidly mounted in the end of cylinder 69. The end 197 of the plunger is formed with an enlarged head of smaller diameter than cylinder 69 but adapted to abut against the inner end of bushing 195 at full stroke and on the suction stroke of the pumping unit. Suitable ring seals 198 are placed in recesses in the bushing 195 and wall 191 to prevent leakage. An annular recess 199, connected to a passageway 200, is provided in the sump wall between ring seals 198 to permit oil to escape therefrom and thereby indicate if the seals are leaking.

Instead of forming cylinder 69 with a narrow end provided with a bushing in which a plunger

having an enlarged head is adapted to reciprocate, the cylinder 69 may be of uniform inside diameter and a piston may be snugly mounted in the cylinder to reciprocate. The piston will be connected to coupling 200" by means of a connecting rod in the same manner as the plunger 193 shown in the drawing.

The end of plunger 193 extending into sump 183 is threaded as shown at 200" to receive a coupling 200". The coupling is rigidly fastened to the end of plunger 193 by means of set screw 200"". Coupling 200" is T-slotted as shown at 201 to receive coupling 203. Coupling 203 is provided with a threaded stem 205 on which is adapted to be screwed pump plunger or piston 207. Piston 207 is rigidly fastened to stem 205 by means of set screw 209. A pump body or cylinder 210 is fastened to the end wall of sump 183 by means of studs 211 mounted in the end wall 212 of sump 183, and nuts 213. The pump body is provided with a flange 215 having a plurality of spaced holes in alignment with studs 211. A suitable ring seal 217 is provided between the end wall 212 and flange 215 to prevent leakage. A throat bushing 219 is rigidly mounted in the pump body 210 in order to provide sliding surfaces for piston 207. A gland 221 is mounted at the end of the pump cylinder adjacent the sump. Gland 221 is held tightly in place by means of studs 223, mounted in the end wall 212 of the sump, and nuts 225. The gland is provided with holes in alignment with studs 223 through which the studs can pass. Gland 221 provides sliding support for the piston 207. Suitable packing 227 is provided between the piston and pump cylinder to prevent leakage. A lantern ring 229 is provided between the piston 207 and pump body 210 to which lubricant is furnished by means of a screw, plunger-type lubricator 231.

The outer end of the pump body is closed by means of screw plug 233 and the body is provided adjacent its outer end with a threaded inlet 235 and a threaded outlet 237.

An angle 239 is bolted to the bottom of end wall 212 of the sump by means of bolts 241. The angle 239 is provided with holes 243 to accommodate bolts 241 and with holes 245 to enable the angle to be fastened to a foundation.

The bore 73 at the left end of casing 1 as shown in Figure 2, is covered with an end plate 247 held in place by studs and nuts, in the same manner as sump 183 on the opposite end of the casing. A ring seal 249 between the casing and end plate prevents leakage. It will be understood that when the left side of the unit is to be used to pump liquid the end plate is removed and replaced with a sump identical with sump 183. Bore 251 through which the adjusting stem will pass when the left side of the unit is used, is plugged with a suitable expansion plug 253 when not in use.

Referring to Figures 2 and 6, mounted on the top of cross-head 53 are two spaced parallel longitudinal bars 255 and 257 extending in the direction of reciprocation of the cross-head, and screwed to the top thereof by means of screws 258. A guide roller 259 is mounted on a flat-headed screw 261 which in turn is screw-fastened into the bottom of bracket 134 at the free end thereof. The guide roller is equipped with roller bearings 263. The space between the guide bars is slightly greater than the outside diameter of the roller so that the roller is free to roll

against the surface of either bar as the cross-head reciprocates. The guide-bars and roller serve to keep the cross-head and cylinders 69 from turning.

Although the unit is shown as being open at the top, it may be supplied with suitable covers adapted to be screw fastened to the top of the casing and sump.

The unit operates as follows: In the position shown in Figure 2 the pump is at the end of its discharge stroke with the stroke adjustment mechanism set for full stroke. Upon further revolution of crankarm 37 the cross-head 53 will be forced to move to the left pulling with it plunger 193 and piston 207. The cylinder 69 is full of oil or other hydraulic fluid sucked in from the casing through valve 79. Since fluid cannot escape from cylinder 69 through either valve 79 or 81 as long as cam 141 is in the position shown, the unit will continue to operate at full stroke unless pressure on the outlet of the pump during discharge exceeds the pressure for which relief valve 122 is set. If this occurs fluid will escape from cylinder 69 through relief valve 122 as the cylinder completes its forward stroke but the forward motion of plunger 193 will stop. Upon the return stroke of the cross-head and cylinder 69, plunger 193 will remain stationary until the enlarged head 197 abuts against the end of bushing 195. The backward movement of cylinder 69 while plunger 193 remains stationary creates suction in cylinder 69, drawing oil into the cylinder from the casing through valve 79 until the cylinder is again filled with oil and is ready for its next forward stroke. Thus, if pressure in the delivery lines exceeds the pressure for which the relief valve is set, plunger 193 will remain stationary while cross-head 53 and cylinder 69 continue to reciprocate through their full stroke.

Now assume that cam 141 is shifted to the left either by means of the motor 151 or by manually turning handwheel 140. When the roller 121 abuts against the cam, the roller is depressed, in turn depressing plunger 119 and ball 111. The loading on spring 113 is not sufficient to keep ball 109 seated under the pressure existing in cylinder 69 and consequently oil will escape from cylinder 69 through valve 81. Cylinder 69 will continue on its forward motion until the end of its stroke, but plunger 193 will immediately stop. The roller 121 rides along the bottom surface of cam 141 and keeps the valve open during the remainder of the discharge stroke. On the suction stroke ball 109 will immediately close valve 81 and thereby prevent suction of air into cylinder 69. On the return stroke cylinder 69 will fill with oil in the same manner described with respect to the operation of the relief valve.

It will be seen therefore that the farther cam 141 is moved to the left the shorter will be the stroke of piston 207 and the less liquid the pump will deliver. The stroke of the pump can be adjusted from zero to full stroke.

Instead of using the check valve and cam mechanism shown and described, control of the stroke of the pump may be attained by substituting therefor a flow control valve which can be adjusted to bleed off any desired amount of hydraulic fluid from cylinder 69 during the forward stroke of the cylinder. Thus a longer or shorter piston stroke will be obtained as less or more fluid is bled off.

Thus, stationary means is provided for adjusting the stroke of the pump or controlling the dis-

charge therefrom at any point during the stroke thereof.

Although the stroke adjusting device has been described and shown in connection with a reciprocating type pump it is adapted for use with other displacement type pumps such as dia-phragm pumps.

When the unit is in operation the casing is preferably filled with oil to the top of the cross-head so that the entire moving mechanism operates in an oil bath, although it is necessary only to maintain the oil level above the level of filter 97. Likewise, it is preferred to maintain the sump full of oil above the level of the moving parts.

By operating the unit as a dual unit with a pump connected to each end of the cross-head, two different chemicals or other liquid can be pumped by the unit and the delivery of each chemical can be independently controlled so that any desired proportion of the two can be delivered.

It is claimed:

1. A variable stroke device comprising a reciprocable cylinder closed at one end, a plunger adapted to reciprocate in said cylinder and extending beyond the other end of said cylinder, an inlet and an outlet valve on said cylinder for admitting and discharging liquid, means for maintaining said outlet valve in open or closed position during any portion of the stroke of said cylinder, and means for reciprocating said cylinder and plunger.

2. A variable stroke device comprising a reciprocable cylinder closed at one end, means for reciprocating said cylinder, a plunger reciprocably mounted in said cylinder and extending beyond the other end thereof, means for admitting liquid to and discharging liquid from said cylinder and means for controlling the volume of liquid discharged from said cylinder on each delivery stroke thereof.

3. A variable stroke device comprising a reciprocable cylinder closed at one end, means for reciprocating said cylinder, a plunger of smaller diameter than said cylinder adapted to reciprocate therein and mounted to prevent leakage of liquid from said cylinder, said plunger having an end extending from the other end of said cylinder and adapted to be loaded, means for admitting liquid to said cylinder and means for automatically discharging liquid from said cylinder at any predetermined point in the stroke thereof.

4. A stroke adjusting device comprising a cross-head adapted to reciprocate along a straight line, a slidably supported cylinder closed at one end rigidly fastened to said cross-head with the axis thereof parallel to the line of motion of said cross-head, a plunger slidably mounted in said cylinder with one end thereof extending beyond the other end of the cylinder, the internal diameter of said cylinder being substantially greater than the diameter of said plunger except adjacent the end from which the plunger extends, means for admitting liquid to and discharging liquid from said cylinder, means for automatically opening said liquid discharge means at any predetermined point in the stroke of said cylinder, a crank-arm mounted to rotate in said cross-head and to slide therein in a direction perpendicular to the direction in which the cross-head reciprocates, a crank to which said crank-arm is fastened and a crankshaft fastened to said crank.

5. A stroke adjusting and piston actuating mechanism comprising a cross-head, means for reciprocating said cross-head, a pair of cylinders closed at one end fastened to opposite sides of said cross-head with the axes thereof extending along lines parallel to the direction of reciprocation of the cross-head, means for slidably supporting said cylinders, at least one of said cylinders having means for admitting liquid thereto, and means for discharging liquid therefrom, during any predetermined portion of the stroke thereof, and a plunger slidably mounted therein, one end of which plunger extends outside the other end of said cylinder.
10. 6. A stroke adjusting and piston actuating mechanism comprising a cross-head, means for reciprocating said cross-head, a pair of slidably supported cylinders closed at one end fastened to opposite sides of said cross-head with the axes thereof extending along lines parallel with the direction of reciprocation of said cross-head, a plunger slidably mounted in each cylinder, said plungers being substantially smaller in diameter than the inside diameter of said cylinder except at the end of said cylinders, said plungers extending outside the other end of said cylinders, means for admitting liquid to said cylinders, means for automatically discharging liquid from said cylinders during any portion of the stroke thereof and means for discharging liquid from said cylinders when the pressure therein reaches a predetermined amount.
15. 7. An adjustable stroke pumping mechanism comprising a stationary cylinder and a reciprocable cylinder, a plunger slidably mounted in said stationary cylinder and a plunger slidably mounted in said reciprocable cylinder said plungers being connected to operate as a unit, an inlet and an outlet in said stationary cylinder, means to admit liquid to said reciprocable cylinder during its suction stroke, means to automatically discharge any predetermined amount of liquid from the reciprocable cylinder during its forward stroke and means to impart reciprocating motion to said reciprocable cylinder.
20. 8. Mechanism in accordance with claim 7 in which the plunger slidably mounted in the reciprocable cylinder snugly fits in the end of the cylinder but is of smaller diameter than the inside diameter of that portion of the cylinder remote from the end from which the plunger protrudes and said plunger has an enlarged end inside the cylinder to enable the end of the cylinder to positively engage the plunger during the suction stroke.
25. 9. An adjustable stroke displacement pump comprises a pair of oppositely disposed stationary cylinders, a pair of oppositely disposed reciprocable cylinders closed at one end, a common means for imparting reciprocating motion to said reciprocable cylinders, a piston slidably mounted in each of said stationary cylinders and a plunger slidably mounted in each of said reciprocable cylinders and extending beyond the other end thereof, each of said reciprocable cylinders being of smaller internal diameter at its open end than throughout the remainder thereof and each plunger having an enlarged end inside the cylinder adapted to abut against the narrow end of the cylinder; the piston and plunger on each side of the reciprocating means being connected to move as a unit, means on each reciprocable cylinder for admitting liquid thereto during the suction stroke and means on each reciprocable cylinder for automatically discharging any de-

sired amount of fluid therefrom during the discharge stroke.

10. A pump in accordance with claim 9 comprising means for automatically discharging liquid from said reciprocable cylinders when the pressure therein reaches a predetermined amount.

11. A pump in accordance with claim 9 in which the means for automatically discharging any desired amount of fluid from the reciprocable cylinders during the discharge stroke comprises a ball check valve mounted on each cylinder, a plunger engaging the ball in each valve and adapted to unseat the ball and open the valve when pressure is applied to the plunger, and a separate movable cam adapted to engage each plunger at any selected point in the stroke of the cylinder whereby the stroke of each piston can be independently controlled.

12. A stroke adjusting device for a displacement type pump comprising a reciprocable cylinder open at one end, an element mounted to reciprocate in said cylinder, said element extending through the open end of said cylinder, means for admitting liquid to the space between the closed end of said cylinder and said element during the suction stroke of the pump and means for controlling discharge of liquid from said cylinder at any time during substantially the entire delivery stroke of the pump.

13. A device for controlling the discharge from a displacement type pump comprising a reciprocable cylinder open at one end, an element adapted to reciprocate in said cylinder and extending through the open end of said cylinder, means for admitting liquid to the space between the closed end of said cylinder and said element during the suction stroke of said pump, means for optionally discharging liquid from said cylinder during the discharge stroke of the pump, and adjustable stationary means for opening said discharging means at any time during operation of the pump and thereby regulate the movement of said pump displacing element.

14. A stroke adjusting device in accordance with claim 12 in which said means for admitting liquid to said cylinder is a ball check valve and said means for controlling discharge of liquid from said cylinder comprises a ball check valve, a plunger adapted to be depressed against and unseat said last mentioned valve, and an adjustable cam for engaging and depressing said plunger at substantially any point in the stroke of said cylinder.

15. A stroke adjusting device for a displacement type pump comprising a horizontally disposed cylinder, an element extending beyond one end of said cylinder, mounted to reciprocate therein, means for reciprocating said element, means for transferring the reciprocating motion of said reciprocating means to the displacement

element of said pump through a liquid medium, means on the lower side of said cylinder for admitting liquid to said cylinder during the suction stroke of said pump while preventing discharge of liquid during the discharge stroke and means at the top of said cylinder for controlling discharge of liquid therefrom at any time during substantially the entire delivery stroke of the pump while preventing intake of liquid or vapor therethrough during the suction stroke of the pump.

16. A device in accordance with claim 13 in which said adjustable stationary means is adapted to automatically open said discharging means at any selected point during the discharge stroke of the pump and said discharging means is adapted to automatically close at the end of the discharge stroke of the pump.

17. Mechanism for automatically discharging fluid from a reciprocating cylinder at any desired point in the stroke thereof comprising a valve mounted on said cylinder adapted to be normally held in closed position, an element one end of which engages said valve in such manner as to enable said valve to be opened upon exerting pressure on the end of said element opposite to that which engages the valve, and an elongated stationary cam adjustable in the directions of reciprocation of said cylinder adapted to contact and exert pressure on the said opposite end of said element during a predetermined portion of the stroke of said cylinder.

18. Mechanism in accordance with claim 17 in which the cam is mounted to travel on a stationary, rotatable stem threaded to engage threads on said cam.
